PHONOGRAPH RECORD CABINET

James R. Roads, Washington, D. C.

Application March 18, 1939, Serial No. 262,684

4 Claims. (Cl. 312—17)

This invention relates to improvements in filing cabinets designed, particularly, for the filing or temporary storage of record discs for phonographs.

The primary object of the invention is to provide a cabinet having a series of disc holders each of which is provided with means for partially removing the individual holder from the cabinet to permit removal of the record, these means being so arranged as to permit each one to be individually actuated without interference from the juxtaposed holders.

A further object is to provide the holders with means or data for identifying the records stored therein, the identifying data being arranged on the holders so as to insure the data on all the holders being fully exposed to view at all times.

Another object of the invention is to provide the holders with means for partially withdrawing them individually from the cabinet, such means presenting ample surface for carrying the record-identifying data.

A still further object is to provide a series of holders with a finger extension on each holder, but with said extensions arranged in groups in different planes, with one or more holders interposed between any two contiguous extensions of a group, whereby all the extensions are spaced sufficiently apart, one from the other, so as to permit any one of them being actuated without accidentally engaging a second extension at the same time.

Another object is to provide the cabinet with holders pivoted to rock forwardly and rearwardly therein, with the pivotal center located forwardly of the center of gravity of the holder even when the latter is in its forwardly tilted position, whereby the holder will automatically return to its rear or inner position by gravity, in the absence of a record.

Another object is to provide a record holder pivoted in the cabinet and formed with a bottom or record-supporting wall slanting inwardly, the inclination of said bottom wall being such that, with the holder in its inner or rearward position, a record deposited in such holder will immediately roll down into the holder, this movement of the record being augmented by gravity and the momentum of the record. Thus, restoration of the records to the holders is greatly simplified and does not require the user to restore the holder to its inner or normal position after placing a record therein.

With these and other objects in view, the invention consists in certain details of construction

and combinations and arrangements of parts, all as will hereinafter be more fully described, and the novel features thereof particularly pointed out in the appended claims.

In the accompanying drawing—

Figure 1 is a perspective view illustrating the present invention in connection with a construction wherein the cabinet casing is shown more or less diagrammatically;

Fig. 2 is a front elevation of the structure disclosed in Fig. 1; and

Fig. 3 is a vertical sectional view on the line 3—3 of Fig. 2.

The casing 10 of the cabinet may, of course, take any desired shape or design although it is illustrated in the present instance of plain rectangular shape, open at the front for removal and replacement of the records. Pivoted on a pivot pin 11 in the interior of the casing are a plurality of holders each preferably capable of receiving a single disc record 12. Each holder comprises opposite side walls, 14, 15, spaced apart by a filler 16 forming the bottom and back of the holder and, in instances where only one record is stored in each holder, of a thickness substantially corresponding to that of the record. The individual holders may be held slightly spaced apart by spacer elements 13 extending forwardly from the rear wall of the housing. Thus, the side walls and filler form a cavity for reception of the record and, as will be observed in Fig. 3, the pivot pin 11 is so located with the center of gravity of the individual holders that the normal tendency of the latter is to tilt inwardly by gravity to the position in which the holder is illustrated. It will also be observed that the edge of the filler forming the wall of the recess in each holder is somewhat dished rearwardly of the pivot pin, this portion of said wall, indicated at 18, preferably conforming to the curvature of the perimeter of the disc. On the other hand the portion of said wall indicated at 19, or in advance of said pivot pin, is struck on a curve of greater radius so that when a holder is tilted forwardly, the disc tends to roll toward the front of the cabinet. However, when the disc is removed from its holder, the latter will tilt backward by gravity to its normal position and, likewise, with the empty holder in normal position, the disc, when replaced therein, will tend to roll to the rear of the holder because of the dished portion 18.

As previously stated, each holder is preferably adapted to hold only a single record and, consequently, is rather thin, so that when a number of them are assembled in a cabinet, it would ordi-

narily be difficult to tilt one particular holder. It should also be mentioned that the holders must be assembled rather close to each other in order to minimize the over-all dimensions of the cabinet. 5 In the present construction, this difficulty is overcome by forming each holder with a finger extension projecting forwardly therefrom with the several extensions arranged in groups each disposed in a different plane and with at least one 10 holder interposed between each two contiguous extensions in a given group. For instance, where the extensions are arranged in only two vertically spaced groups, as in the structure illustrated, one set of alternate holders is formed with extensions 15 20, and the other set of alternate holders with extensions 21. The extensions 20 are longer than extensions 21, but the latter project an appreciable distance above extensions 20, so that the operative portions thereof, or the finger-engaging 20 portions of the two sets or groups are disposed in planes spaced vertically apart, and the extensions of each group are also spaced laterally apart sufficiently to permit any one extension to be depressed without unintentionally depressing a 25 second extension at the same time.

In the preferred embodiment of the invention, these extensions are formed integrally with the filler pieces 16, projecting forwardly at the bottom forward edge of the holder. It is also preferred that the individual extensions be provided with beveled or inclined upper or end surfaces, as indicated at 22. Due to the fact that single record holders are so thin, there is very little surface on which to impress data identifying the 30 record carried in the holder. It is intended that each record carry some identifying means or data such as the numeral "17" appearing on the record illustrated in Fig. 3. The records, with their identifying data are suitably listed or indexed, and the data for each record also impressed on the beveled or inclined surface of the extension on the holder for that particular record. Thus, although the title appearing on the record may be completely concealed, it is an 35 easy matter to select and depress the holder containing the desired record. In this connection, it will be noted that the lateral spacing of the extensions of the respective groups and the vertical spacing of the data-bearing portions of 40 the several groups, results in data-bearing portions of all the extensions being fully open to view at all times. Thus, removal of a particular record can be accomplished with facility due to the fact that all identifying data is fully exposed 45 and any one extension can be readily depressed without interference from the adjacent extensions. 50

It will be understood that, when a holder is depressed, and the record rolls toward the front 60 thereof, it will be retained in the curved portion 19 of the holder bottom, as indicated in dotted lines in Fig. 3. In other words, it will be only partially ejected and complete removal is accomplished by the operator lifting it out of the 65 holder.

When the holder is tilted forwardly and the record held in the dished portion 19 thereof, the center of gravity of the combined holder and record is located forwardly of the pivotal center 70 11, so that they will remain in this position until the record is removed from the holder. However, it will be observed, in Fig. 3, that the center of gravity of each holder is located rearwardly or inwardly of the cabinet with respect 75 to the pivotal center 11 so that, when the record

is removed therefrom, the holder will return, by gravity, to its normal inner or rearwardly tilted position. It will, further, be observed, in Fig. 3, that the curved portion 19 of the bottom wall of the holder presents a comparatively steep 5 surface and, when a record is restored to the holder, it will immediately start to roll down this inclined surface, and gravity and the momentum of the record will cause it to assume the position in which it is shown in full lines in Fig. 3. Thus, 10 full restoration of the record to the holder is accomplished merely by the user lightly placing the record in the holder. The holder having automatically returned to its inner position, as previously described, this full restoration of the 15 record is accomplished merely by this single act of placing the record on the forward edge of the bottom of the holder. This is very simple, as compared with those structures wherein the record 20 must be placed in the holder and the holder manually tilted to its normal position in the cabinet.

What I claim is:

1. In a phonograph record disc cabinet, a disc holder comprising side walls and a filler member between said walls constituting the bottom of the holder, said holder being pivoted to swing forwardly and rearwardly in the cabinet, the center of gravity of the holder being located rearwardly of the holder's pivotal center at all 30 times, the bottom surface of said holder supporting the record having dished, concave portions forwardly and rearwardly of said pivotal center with the two concave portions struck on different centers, the forward dished portion being of sufficient depth to retain the record in the holder when the latter is swung forward. 35

2. In a phonograph record disc cabinet, a disc holder comprising side walls and a filler member between said walls constituting the bottom 40 of the holder, said holder being pivoted to swing forwardly and rearwardly in the cabinet, the center of gravity of the holder being located rearwardly of the holder's pivotal center at all times, the bottom surface of said holder supporting the record having dished, concave portions forwardly and rearwardly of said pivotal center with the two concave portions struck on different centers, the forward dished portion being of sufficient depth to retain the record in 45 the holder when the latter is swung forward, the center of gravity of the holder and record combined when the latter is held in said forward dished portion being located forwardly of the 50 pivotal center of the holder. 55

3. In a phonograph record disc cabinet, a holder pivoted to swing forwardly and rearwardly of the cabinet, the pivotal center of the holder being located forwardly of the center of gravity thereof whereby the holder will swing rearwardly 60 by gravity to its normal position in the absence of a record, said holder having a bottom formed with a concave surface rearwardly of the pivotal center of the holder and in which the record is normally retained and a second concave surface 65 in said bottom in advance of said pivotal center, the depth of said second concave surface being such as to retain a record therein when the holder is tilted forwardly and the inclination of the 70 forward portion of said second concave surface being such that a record disc deposited thereon with the holder in its normal position will roll past the pivotal center of the holder onto said rear concave surface by reason of the momentum 75 75

acquired by said record in descending said inclined portion.

4. In a phonograph record disc cabinet, a holder pivoted to swing forwardly and rearwardly of the cabinet, the pivotal center of the holder being located forwardly of the center of gravity thereof whereby the holder will swing rearwardly by gravity to its normal position in the absence of a record, said holder having a bottom formed with a concave surface rearwardly of said pivotal center and in which the record is normally
- 5 retained and a second concave surface in said bottom in advance of the pivotal center of the holder, the inclination of the forward portion of said second concave surface being such that a record disc deposited thereon with the holder in its normal position will roll past the pivotal center of the holder onto the rear concave surface by reason of the momentum acquired by said record in descending said inclined portion.
